5 Claims. (Cl. 68—23)

This invention relates to clothes washing machines and more particularly to a combined washing and centrifugal extracting machine, wherein the extractor basket operation is automatically controlled so as to prevent the occurrence of excessive gyration of the extractor basket and the destructive effects resulting from such excessive gyration.

Numerous attempts have been made to provide a centrifugal extractor suited for domestic laundry use which would operate efficiently under the varying load and speed conditions attending such use. It has been appreciated by those working in this art that a rigidly supported rotating extractor necessitated the use of a massive base structure to absorb and dampen the forces transmitted thereto due to the rotation of the extractor basket. It has also been appreciated that a basket rigidly supported produced high bearing loads and that the required base and bearing structure resulted in a machine involving such weight and expense that it would be unsuited for domestic use. To overcome in part the defects of a rigidly supported extractor assembly, it has been proposed to flexibly mount the extractor unit so that the basket and shaft carried thereby may move within certain limits so as to accommodate and dissipate the forces developed by basket rotation.

A familiar characteristic of centrifugal extractors is their comparative stability or dynamic balance after they have passed through their critical speed of rotation to the high speed required for centrifugal extraction. It has been observed that as the rotation of the basket increased from zero to extracting speed, there is a marked tendency for the basket to precess or gyrate about a center. In a unit that is mounted for free movement about its support, there is a tendency for the basket to follow an increasingly larger path of precession as the rotational speed is increased toward extracting speed. This precession or gyration may be so excessive in the event of out-of-balance loads in the basket, that the basket will strike the sides of the casing in which it is mounted and adversely affect the bearings and mountings of the basket before it acquires extracting speed and dynamic stability.

Another known characteristic of centrifugal extractors is that where an externally applied force acts to accelerate the speed of precession as the rotation speed of the basket is increased, the basket will tend to quickly acquire its position of greatest stability or dynamic balance.

According to my invention, I propose to take

advantage of this last-mentioned characteristic and provide a method and apparatus for accelerating the travel of the basket and its shaft along its path of precession so that the rotating basket will acquire a position of dynamic balance and stability without the production of excessive destructive gyroscopic movements.

Accordingly, it is among the objects of my invention to provide a washing machine having a centrifugal extractor mounted to precess in response to rotation thereof and in which the travel of the extractor through its precessional path is accelerated by a device which progressively decreases the magnitude of the precessional path.

It is a further object of my invention to provide a washing machine according to the preceding object in which the device for progressively decreasing the magnitude of precession includes a friction-drive connection that automatically moves toward and away from a driving position in response to the movement of the extractor basket away from its position of maximum stability of dynamic balance.

It is a further object of my invention to provide a washing machine having an extractor arranged according to the preceding objects, wherein a horizontally arranged rotating disc is frictionally connected to one end of a link, which link is connected at its other end to the shaft of the extractor basket so that the rotation of the disc operates to advance and accelerate the extractor basket shaft through its path of precession.

It is a further object of my invention to provide a washing machine according to the preceding objects in which the driving effect of the disc on the link varies in accordance with the position of the link with respect to the center of the disc and this last-named position is in turn controlled by the position of the extractor basket shaft with respect to its axis of gyration.

It is a further object of my invention to provide a washing machine having an extractor basket mounted on a shaft to rotate about the axis of said shaft when dynamically balanced and to precess with respect to its dynamically balanced position as the rotation of the shaft on its axis is increased from zero to extracting speed and wherein said shaft is journaled to one end of a link and the other end of the link is frictionally connected to a disc whereby the shaft is accelerated in its travel through its precessional path by the rotation of the disc at a speed exceeding the speed of precession resulting from the rotation of the shaft and basket.

It is a further object of my invention to pro-

vide a washing machine constructed according to the preceding objects in which means are provided to rock the extractor basket about its mounting to effect a washing of the clothes and the means to wash the clothes are operatively connected to the means for advancing the shaft through its precessional path so that the washing means and the precessional advance means successively act on said basket and shaft, during the washing and extracting operations, respectively.

It is a further object of my invention to provide a combined washing and extracting machine in which an extractor basket is fixed to one end of a substantially vertical shaft, and flexibly mounted at the other end so that the shaft and basket may move in response to means for rocking the shaft to effect washing and precess in response to rotation of the extractor basket and wherein the precession of the shaft during extraction is accelerated by a device operating independently of the means to effect washing.

It is a further object of my invention to provide a combined washing and extracting machine having a basket mounted on a substantially vertical shaft, washing means to rock the shaft about its lower end, precession accelerating means to advance the shaft through its path of precession and means connecting the washing means and the precession accelerating means, whereby the precession accelerating means is rendered operative upon rendering the washing means inoperative.

It is a further object of my invention to provide an extractor mounted to precess in response to rotation of the extractor basket and wherein a link journaled at one end to the extractor is pivoted intermediate its ends so that the other end of the link follows a path corresponding to the precessional path of the extractor and advances through its path in a direction opposite to the direction of precession of the extractor basket.

It is a further object of my invention to provide a device for accelerating the precession of an extractor basket wherein a disc supplying the accelerating force rotates in a direction opposite to the direction followed by the extractor basket through its path of precession.

Another object of this invention is to provide a laundry machine having a container mounted on a rotatable shaft wherein the various laundry operations of washing, rinsing and extracting may be carried out, including mechanism adapted to perform the respective operations, and mechanism for accelerating the precessional movement of the shaft when the same is rotated, and a suitable timing and control device effective to operate the said mechanism to perform their respective functions and operations in a predetermined sequence.

The foregoing and other objects of the invention will become more apparent and better understood after consideration has been given to the following detailed description taken in conjunction with the accompanying drawings, wherein like reference characters denote corresponding parts, and wherein:

Figure 1 is a fragmentary sectional view through laundry apparatus constructed according to my invention;

Figure 1^a is an enlarged sectional detail taken on the line 1^a—1^a of Figure 1;

Figure 2 is a sectional view taken on the line 2—2 of Figure 1;

Figure 3 is a fragmentary sectional view taken on the line 3—3 of Figure 2;

Figure 4 is a medial sectional elevational view illustrating an extractor tub of a two tub laundry unit embodying my present invention;

Figure 5 is a top plan view with parts thereof broken away to illustrate the driving mechanism for the extractor container;

Figure 6 is a fragmentary sectional detail taken on the line 6—6 of Figure 7;

Figure 7 is a fragmentary sectional view with parts broken away and taken generally on the line 7—7 of Figure 4;

Figure 8 is a fragmentary sectional view taken on the line 8—8 of Figure 7, and

Figure 9 is a diagrammatic sketch.

With reference to the accompanying drawings and particularly to Figures 1, 2 and 3, there is illustrated the present invention as applied to a laundry machine of the type wherein washing, rinsing and extracting operations are carried out in a single tub comprising a substantially rectangular casing 10, suitably secured to and supported by the depending flange 11 of a base plate 12. The plate 12 may be supported in any suitable manner, as for example, on resilient members 13, as illustrated in Figures 1 and 3. The casing 10 is provided with a top 14 having a centrally disposed flanged opening 15 therein, thereby affording access to the laundry mechanism disposed within the casing 10. A suitable cover 16 hinged at one side of the opening 15 serves as a closure for the opening. A conduit 17 leading from a valve 18 and terminating in a down-turned nozzle 19 projecting through the cover 16 serves to direct a spray of water into a container positioned within the casing 10.

Mounted within the casing 10 on suitable angle members 20 secured to the inner side wall of the casing is a shell 21, substantially oval in cross-section, and formed with an inwardly extending trough 22 about its lower edge. The bottom of the trough 22 is downwardly inclined and terminates at one side of the casing in an outlet 23 which may be connected by means of a conduit 24 to any suitable drain. Disposed within the shell is a combined washing, rinsing and extracting container 28, which is generally spherical in contour, having a flanged opening 29 in the top thereof through which clothing and washing fluid are adapted to be introduced into the container.

Secured on the lower inner surface of the container are suitable washing projections 30 against which the clothing is adapted to be rubbed during the washing and rinsing cycles of operation of the laundry machine. Extending through the wall of the container at the line of greatest diameter are a plurality of small apertures 31 disposed in a ring about the container and through which fluid within the container and the clothing therein disposed is adapted to be expelled by centrifugal force upon rapid rotation of the container. The apertures 31 are normally maintained sealed by a resilient band 32 mounted on the exterior surface of the container and maintained in position by spaced angular segments 33. Spaced springs 34 maintain the band under tension to seal the openings until the centrifugal force overcomes the spring tension and releases the fluid through the openings 31. An inclined drip rim 35 secured to the lower outer surface of the container below the apertures 31 serves to direct the expelled water from the container into the trough 22.

The container 28 is secured to the upper surface of a plate 36 integrally formed on the upper end of a drive shaft 37 which is rotatably jour-

naled within a tubular housing 38. The lower end of the housing is supported by a yoke 39, the ends of which are pivotally supported in trunnions formed on the end of a second yoke 40. The yoke 40 extends substantially parallel with the base plate 12 and is formed with a tubular shank 41 which is rotatably mounted upon a shaft 42 extending between spaced bracket members 43 secured on the surface of the base plate 12. It will be seen that by the foregoing structure a support is provided for the shaft 37 so that the shaft is capable of substantial universal movement about its supporting point and thereby is mounted for gyratory movement. Between the upper end of the housing 38 and the lower surface of the plate 36, there is disposed a roller bearing ring 44 and a coupling sleeve 45 formed of two relatively movable intersecting members 45^a and 45^b. For resiliently supporting the upper end of the housing in a substantially vertical position and for urging the return of the housing to such position when forces have caused it to assume an angulated position with respect to the vertical, there is provided a plurality of elongated coil springs 46 extending radially from a ring 47 encircling the upper end of the housing to bracket members 48 mounted in the corners of the casing 10.

The lower end of the drive shaft 37 extends below the housing 38 and has freely rotatable thereon a pulley wheel 51 which is maintained thereon by means of a thrust bearing 52 and a nut 53. Slidably splined to the shaft 37 between the pulley 51 and the lower end of the housing 38 is a drum 54 having a friction shoe 55 secured to the lower surface thereof and engageable with the upper face of the pulley 51. The drum is normally urged downwardly and into engagement with the pulley wheel 51 by means of a coil spring 56 encircling the shaft 37 between the hub of the drum 58 and the lower end of the shaft housing 38, to effect a driving connection between the pulley 51 and the shaft 37 for rotating the latter. The drum 54 is provided with an outwardly extending flange 57 having a friction shoe 58 secured to the lower surface thereof. A second drum 59 encircling the drum 54 is formed with an inturned flange 60 against which the friction shoe 58 bears when deceleration of the shaft 37 is to be effected and to disengage the shaft from the pulley 51. The drum 59 which serves to move the drum 54 along the shaft 37 against the force of the coil spring 56, is actuated by a disc 61 formed with a central sleeve 62 which encircles the lower end of the housing 38. The disc 61 is supported on the lower ends of links 63 which are pivoted to the ends of crank arms 64 mounted on the rod 65 which is journaled in a suitable bearing formed on the yoke 39. Rotative movement is imparted to the rod 65 by means of a lever 66 adapted to be actuated by a wire 67 leading from the timing and control mechanism diagrammatically indicated in Figure 2 and designated with the reference character "A." The timing and control mechanism which may be employed in the operation of the subject machine is disclosed in detail and claimed in United States Letters Patent 2,344,253 which issued to me March 14, 1944.

For washing clothing, the container 28 is oscillated within the shell 21 by applying a reciprocating force to the upper end of the shaft 37 to rock or oscillate the shaft about its pivotal support. With reference to Figure 1, the mechanism for oscillating the container 28 is housed within a

casing 70, suitably supported from the inner side wall of the casing 10 by means of a bracket 71. Rotatably mounted within the casing 70 is a drive shaft 72 which extends downwardly through the lower wall of the casing and has mounted thereon a pulley wheel 73. The upper end of the shaft 72 carries a pinion 74 which is adapted to mesh with a gear wheel 75 freely rotatable on the lower end of a shaft 76. The upper surface of the gear wheel 75 is provided with a diametrically extending slot 77 which is adapted to receive a pin 78 extending through the lower end of the shaft 76. The gear wheel 75 is slidably in mesh with the pinion 74 and rotates continuously during the operation of the machine, and the shaft 76 is operatively connected to the gear wheel 75 by bringing the slot 77 of the gear wheel into engagement with the pin 78. For shifting the gear wheel 75 longitudinally of the shaft 76, there is provided a yoke 79 engageable between spaced collars keyed to an extension shaft 81 formed on a cap 82 threaded on the hub of the gear wheel 75. The yoke 79 is actuated by means of a rod 83 having a lever arm 84 which is actuated by means of wire 85 operatively connected to the timing mechanism "A". The extension shaft 81 has secured to its lower end a pulley wheel 86. The drive shaft 72 is provided with a worm 87 which meshes with a worm wheel 88 mounted on the end of a shaft 89 and serves to drive the operating mechanism of the timing and control device "A." as described in my aforesaid patent.

The shaft 76 is journaled in an upwardly extending housing 90 formed integrally with the gear case 10. A bracket 91 extending from the housing 90 to the wall of the casing 10 serves to support the upper end of the housing in a substantially rigid position. Formed on the upper end of the shaft 76 is a crank arm 92 which has associated therewith a universal coupling member 93. A connecting rod 94 extends between the coupling member 93 on the crank arm 92 and a similar coupling member 95 formed on the sleeve 45 encircling the shaft 37. A spring 96 extending transversely from the crank end of the rod 94 to the wall of the casing 10 serves to urge the crank arm out of alignment with the shafts 37 and 76 to insure longitudinal free movement of the connecting rod 94 when the shaft 76 is disconnected from the driving gear 75. A spring pressed pawl 97 mounted on the connecting rod 94 and engageable with a rack 97^a formed on the lower surface of the plate 36 effects a step-by-step rotation of the container 28 during the linear oscillation thereof. This rotative movement is effective to change the position of the clothing within the container with respect to the path of oscillation to effect a uniform washing and/or rinsing of the clothing.

The pulley wheel 51 on the shaft 37 and the pulley wheel 73 on the lower end of the shaft 72 are operatively connected by means of a belt 98 to a driving pulley 99 mounted on the lower end of the armature shaft of a motor 100. Motor 100 is pivotally mounted in a bracket 101 secured to the wall of the casing 10, and the belt 98 is tensioned by a spring 102 extending between the motor 100 and a bracket secured to the casing wall.

With reference to Figures 2 and 3, there is illustrated mechanism for accelerating precessional movement of the shaft 37 to thereby effect a centering or balancing of the container supported upon the upper end of the shaft. This mechanism comprises a shaft 103 journaled in a

housing 104 supported in a bracket 105 secured to a side wall of the casing 10 adjacent that to which the oscillating mechanism is secured. The shaft 103 is rotated by means of a belt 106 extending between a pulley wheel 107 secured to the lower end of the shaft 103 and the pulley wheel 86 associated with the oscillating mechanism. On the upper end of the shaft 103 there is formed a disc 108 adapted to bear upon a bearing ring 109 positioned between the disc and the upper end of the housing 104. Bearing on the upper surface of the rotating disc 108 is a friction shoe 110 which is supported and guided to its position on the disc 108 by the connecting arm 112. Swivelly connected on one end of the arm 112 is a bearing member 111 in which rotates the post 110^a upstanding from the friction shoe 110. The other end of the arm 112 is attached to the shaft 45 by means of the member 45^b of the connecting sleeve. The connecting arm 112 extends substantially at an angle of ninety degrees to the arm 94 and comprises spaced tubular members 114 and 115 and an intermediate sleeve 116 which are maintained in assembled relation by a concentric tubular member 117. The opposite ends of the connecting rod 112 are provided with yokes, one of which is adapted to be connected to the sleeve 111 and the other to the coupling 113. The sleeve 116 is supported in a yoke 118 formed on the upper end of a rod 119. The rod 119 is slidably received within a tubular sleeve 120 formed in an upstanding bracket 121 which is pivoted to the outer end of a bracket 122 secured to the housing 104. A spring 123 extending between the arm 112 and the bracket 122 serves to control the amount of friction between shoe 110 and the surface of the disc 108. The outer end of the arm 83 is adapted to be journaled in a bearing 124 mounted on the surface of bracket 122. An arm 125 is keyed to the rod 83 and has formed on the outer end thereof a ball socket 126. Socket 126 receives the lower end of a rod 127 which is slidably received within a sleeve 128 depending from the arm 112. By this construction, the clutch mechanism for operatively connecting the shaft 76 with gear wheel 75 is interconnected with the mechanism for accelerating precessional movement, so that when the oscillating mechanism operates to effect washing of the clothes within the tub, the arm 112 is raised through the rod 127 to break the contact between the friction shoe 110 and the surface of the disc 108.

With reference to Figures 4 and 5 of the drawings, there is illustrated the extracting unit of a two tub laundry machine having applied thereto my invention for accelerating precessional movement and thereby centering the extractor container during the extracting operation. The apparatus illustrated in these figures includes a casing 128 having mounted therein a cylindrical shell 129, the lower wall of which is inwardly flanged to define a trough 130. The bottom of the trough 130 is downwardly inclined and terminates in an outlet 131 which may be suitably connected to a drain by means of conduit 132. Mounted within the shell 129 is an open topped extractor container 133 having a plurality of openings 134 in the wall portion thereof through which water may be expelled from the clothing disposed therein. A drip rim 135 is secured to the lower portion of the exterior wall of the extractor container and serves to direct fluid flowing from the container into the trough 130. The bottom of the container is secured to a plate

136 formed on the upper end of an operating shaft 137 which is journaled in a housing 138. The housing 138 is supported in a yoke 139, the ends of which are pivoted in the ends of a horizontally disposed yoke 140, the shank 141 of which is rotatably mounted on a shaft 142 supported in spaced bracket members 143. The shaft 137 is provided with a rotatably mounted pulley wheel 144 on the lower end thereof and which is adapted to be operatively connected to the shaft 137 by means of a clutch mechanism broadly indicated by the numeral 145, and which is similar to that hereinbefore disclosed with reference to Figures 1 and 1^a. The apparatus for accelerating precessional movement and thus centering the container 133 includes a casing having a vertical shaft 146 upon which is mounted a pinion 147. The shaft extends downwardly through the casing wall and has secured thereto a pulley wheel 148. Meshing with the pinion 147 is a gear wheel 149 secured to the lower end of a shaft 150 journaled in the vertically extending housing 151. The housing 151 is secured to the side wall of the casing 128 by means of a bracket member 152. The upper end of the shaft 150 is provided with a disc 153, the surface of which is substantially polished to receive a friction shoe 154. Intermediate the lower surface of the disc 153 and the housing 151 is a bearing ring 155. The friction shoe 154 is operatively connected to the shaft 137 by means of a connecting arm 156 which is of construction similar to that hereinabove described and disclosed in Figures 6 and 7. This arm is pivotally supported by means of a guide arm 157 extending from the midpoint of the connecting arm 156 to the outer extremity of the bracket 158 formed on the housing 151. The guide arm 157 is hinged both to the bracket 158 and the arm 156. A spring 159 extending between the arm 156 and the bracket 158 serves to maintain the friction shoe 154 in contact with the upper surface of the disc 153. A plurality of springs 160 extending from the upper end of the housing 138 to spaced points about the tub serve to resiliently center the shaft. A ring-like weight 161 is secured to the bottom of the tub for aiding in balancing the container 133 when it is rapidly rotated for extracting purposes.

50 The pulley wheel 144 on the rotating shaft 137 and the pulley wheel 148 of the centering mechanism are driven by means of a belt 181 connected to the driving pulley 182 mounted on the lower end of the armature shaft of a motor 183. The motor is pivotally supported in a bracket 185 secured to the side wall of the casing 128 and the belt 181 is tensioned by means of the coil spring 184 extending from the motor to the casing wall.

55 The operation of the laundry machine illustrated in Figures 1 to 3 may be manually controlled or may be controlled by suitable timing mechanism such as is described in my aforesaid patent. In the former case, each operation of the machine must be separably instituted and terminated by means of a suitable control. In the latter case, the entire cycle of operations performed by the machine is automatically controlled, but as the operations performed by the machine are the same in either case, for simplification only the operation of the machine as controlled by the automatic timer, generally referred to by the character "A," will be described herein.

60 In such operation of the machine, a water supply conduit, not shown, through which fluid

is supplied to the nozzle 19 is connected to any suitable water supply under pressure and at the desired temperature, and the outlet 23 of the shell 21 is connected to a suitable drain by means of the conduit 24. The electric conduit for conveying current to the motor 100 is connected to a source of current supply.

Clothing and soap are placed in the container 28 and cover 16 is closed, and then the switch is actuated to close the circuit to the motor 100. Simultaneously the timing and control mechanism is initiated. The water supply control of the timing mechanism allows a predetermined amount of water to flow into the container 28. While the water is flowing into the container, the time control mechanism pulls the wire 85 rotating the arm 84 which actuates the yoke 79 to move the gear wheel 75 along the shaft 76 into engagement with the pin 78, thereby connecting the shaft 76 to the drive shaft 72 for rotation in a direction opposite to the rotation of the container shaft 37. The shaft 76 through its associated crank arm 92 and connecting rod 94 oscillates the container 28 for the duration of the washing period provided by the setting of the timing mechanism. Upon each reciprocation of the container 28, the pawl 97 on the connecting rod 94 is effective to rotate the container one notch on the rack formed on the lower surface of the plate 36, thereby continually shifting the clothes within the container with respect to the direction of reciprocation. At the expiration of the washing period, the timing mechanism releases the wire 85, and the gear wheel 75 drops out of engagement with the pin 78, thereby disengaging the shaft 76. Simultaneously the frictional contact between the disc 108 and friction shoe 110 is established. At the same time or immediately thereafter, a force is applied to wire 67 by the timing mechanism, causing the pulley wheel 51 to be operatively connected to shaft 37 for rotating the container. Simultaneously with the release of wire 85, the rod 83 connected to the arm 84 is rotated to cause the rod 127 to drop down and permit the spring 123 to draw arm 112 down so as to establish contact between the friction shoe 110 on the end thereof and the surface of the disc 108. When the container 28 and the shaft 37 upon which the container is mounted are in their normal vertical position, the disc 110 is substantially concentric with the disc 108, and as the axis of the friction shoe 110 and the post 110a attached thereto are the same, no movement is transmitted from the accelerating mechanism to the shaft of the container. As precession develops upon the rotation of the container, the friction shoe 110 is guided to a position with respect to the disc 108, so that a force is applied through the frictional engagement of the shoe and disc to correct the precessional movement and balance the container. Inasmuch as the departure of the shaft 37 of the extractor container from its normal vertical position controls the position of the friction shoe 110 with respect to disc 108, when the container reaches a rotating speed at which it is in equilibrium and not subject to any tendency to precess, the friction shoe 110 is brought into a position concentric with the disc 108 and no longer operates to transmit any force back to the shaft 37 by means of the connecting rod. The timing mechanism operates to keep the container spinning for a period of time sufficient to allow all washing fluid which can be extracted from the clothes to drain from the container through the apertures 78

31, the band 32 unsealing the openings under the centrifugal force of the fluid in the spinning container. When the extracting period is terminated and as the container is permitted to decelerate to a state of rest, any precessional movement that again develops in the container and shaft causes the friction disc 110 to again assume an eccentric position with respect to the driving disc 108, so that it transmits an accelerating force by means of the connecting rod 112 back to the shaft 37, thereby governing and overcoming its precessional movement before the movement becomes severe. It is intended in this invention to use an accelerating force to overcome precessional tendency of the shaft and container.

In the case of the extracting unit illustrated in Figures 4 and 5 of the drawings, the centering device for the shaft 137 upon which the extractor 20 container is mounted is operably connected to the pulley wheel 144 by the belt 181, and is continuously driven. The shaft 150 is back geared to reverse rotation and give slow speed slightly in excess of the speed of precession. When the 25 shaft 137 is operably connected to the continuously driven pulley wheel 144 by the clutching mechanism 145, the centering mechanism is effective to overcome any precessional movement of the container 133 and the shaft 137 upon which it is mounted.

Having thus described my invention, what I desire to obtain by Letters Patent is described in the appended claims.

What I claim is:

1. An extractor comprising a container, a rotatable shaft supporting the container on the upper end thereof, the lower end of the shaft being flexibly mounted to permit the shaft and container to precess in response to rotation of the 35 shaft and container about the shaft axis, a power driven disc rotating on a fixed axis, a rod mounted for reciprocation and operably connected at one end to the extractor shaft to be actuated by precessional movement only of the shaft, a member 40 carried by the rod and engaging said disc, said member being movable across the axis of said disc and being coaxial with said shaft when the extractor shaft is centered, the rotation of said disc being at a speed higher than the precession speed of the extractor shaft and in a direction effective to accelerate precession and thereby center the extractor shaft.

2. In a combined washing and extracting machine, a container adapted to hold clothes and washing fluid, a supporting shaft for the container, means for oscillating the container about a generally horizontal axis to effect washing, means to rotate the container and shaft at high speed to effect extraction, mechanism to prevent excessive precessional movement of the shaft 55 while the container is being accelerated through a critical speed with an out-of-balance load comprising friction drive means for accelerating the precessional movement by applying a force normal to the shaft adjacent to the container in the path of the container and shaft precession.

3. A washing machine comprising a container, a rotatable shaft supporting said container on its upper end, means for rotating said shaft at high speed for extracting, said shaft supported for gyratory movement adjacent its lower end, means for oscillating said shaft about a horizontal axis to effect washing of the clothes and means to overcome excessive gyration of the shaft and container during that phase of the extracting oper-

ation when the container is rotating through a critical speed with an out-of-balance load, said means comprising mechanism for applying a force normal to the shaft in the direction of its precessional path to accelerate precession and effect a centering and balancing of the shaft and container.

4. A washing machine comprising a container, a rotatable shaft supporting said container on its upper end, said shaft being supported for gyroscopic movement adjacent its lower end, means for rotating said shaft at high speed for extracting, means for oscillating said shaft in a substantially vertical plane about its support for washing, driving means for operating said rotational means and said oscillatory means, and mechanism to prevent excessive precessional movement of said container when said container is being rotated for extracting purposes comprising a shaft having a fixed axis laterally spaced from the true vertical axis of the container shaft and adapted to rotate at a speed greater than the speed of precession of the shaft supporting said container, and a lateral connecting arm between said shafts which is responsive to the precession 25

of the shaft of said container to transmit an accelerating force to said container shaft in the direction of precession.

5. A combined washer and extractor comprising a clothes container, an upright shaft supporting said container, means for supporting said shaft and container for rotary movement and precessional movements and rocking movement about two horizontal axes, means for agitating material within said container during the washing operation by rocking said container and shaft about one of said axes, power driven means for imparting reciprocating movements to said agitating means, driving means for rotating said shaft during the extracting operation, means for controlling the precession of said container and shaft during the extracting operation, means for disconnecting said agitating means from said power driven means and connecting said driving means to said shaft, and means for controlling the operation of said precession controlling means to render the same operative upon connection of said shaft to its driving means.
